UNITED STATES PATENT OFFICE.

FRANK O. WELLS, OF GREENFIELD, MASSACHUSETTS.

HEXAGONAL DIE.

Application filed July 3, 1924. Serial No. 723,894.

To all whom it may concern:

Be it known that I, FRANK O. WELLS, a citizen of the United States, residing at Greenfield, in the county of Franklin and State of Massachusetts, have invented new and useful Improvements in Hexagonal Dies, of which the following is a specification.

This invention relates to improvements in thread forming dies or screw plates of the hexagonal type in which a slit is formed in one side, and an adjusting screw is provided for varying the diameter of the thread being cut by drawing the sides together, or, by permitting the slit to open when rotated outward. Broadly, it comprises a die formed with a plurality of thread forming lands which extend parallel with the axis and of a length which is equal to the thickness of the stock composing the die. Located intermediate of the length of the die and spanning the arc shaped space between the lands is a strengthening rib which is formed with inclined sides which taper back substantially to the outer marginal edges of the die for permitting the chips to be radially thrown away from the cutting edges and for providing free and easy access to the lands for thoroughly lubricating the work when a thread is being cut. The construction and formation of the strengthening rib being such that the stresses imparted by the lands when a thread is being cut are distributed both axially and radially. Heretofore, it has been a common practice to arrange or locate the strengthening rib between the lands substantially at one side or edge of the die instead of locating it in a plane represented by the median line of the die or screw plate. In the present improvement the strengthening rib is located an equal distance from the opposite sides or faces of the die.

Referring to the drawings:

Fig. 1 is a plan view showing the four thread forming lands and the slit at one side with the adjusting screw spanning the slit for accurately varying the diameter of the thread being formed or cut on the work.

Fig. 2 is a vertical sectional view on the line 2—2 of Fig. 1 looking in the direction of the arrows showing two of the lands, and the oppositely located inclined sides of two of the recesses or grooves which extend from the marginal edge to the cutting edges of the lands up to the strengthening rib, and

Fig. 3 is a horizontal sectional view on the line 3—3 of Fig. 1 showing two of the lands and another one of the strengthening ribs between these lands and the adjacently located inclined grooves.

Referring to the drawings in detail:

1 designates the body portion of the die which is formed with a slit 2 in one side which is spanned and connected by the adjusting screw 3 for accurately varying the diameter of the thread to be cut. When the screw is rotated outward the die will spring open. It is reduced in size when the thread is turned inward. This die, as shown, is formed with four inwardly projecting ribs 4, 5, 6, and 7, which extend radially inward into the opening 1' and on each of their inner edges is cut the thread forming teeth 8, 9, 10, and 11. Formed between the projecting ribs 4, 5, 6, and 7 on one side of the die are the inclined shaped recesses 12, 13, 14, and 15 and on the other side of the die are the correspondingly shaped recesses 16, 17, 18, and 19 as shown in the sectional views in Figs. 2 and 3. The forward edges of these inclined shaped recessed portions terminate slightly back of the cutting teeth 8, 9, 10, and 11 as shown at 20 producing the transversely located openings 22 which connect the opposite sides of the recesses. These edges are located in a plane represented by the median line 20' in Fig. 2. When the device is used to form a thread on a bolt or other piece of work the inclined recesses 12 to 15 on one side and the inclined recesses 16 to 19 on the other side as well as the openings 22 serve as large openings to permit the severed chips or removed metal to freely flow outward away from the work on which a thread is being cut. At the same time the centrally disposed ribs 20 serve to firmly retain and support the cutting lands 4, 5, 6, and 7. These centrally disposed connecting ribs between the lands serve the double purpose of firmly retaining them in the plane of the median line 20—20' and also axially or transversely support the lands for maintaining the same in their original position without any danger of 105 their being twisted out of alignment. Another important feature of the inclined recessed portions is to permit free access to the threads of the lands for oiling.

It will also be observed that the cross-section of the supporting ribs 20 is substantially that of a pyramid with the apex

at 20' and the base at the outer edges of the hexagonal die. This pyramidal shaped section is indicated at 21 in Figs. 2 and 3 whereby the ribs 20 between the lands are supported or braced in opposite directions along the axial line 22-22. An important feature is that the hexagonal shaped die may be used with an ordinary wrench or, in a die stock.

10. It will be observed that the cutting lands 4, 5, 6, and 7 terminate in the borders of the cone shaped openings 12, 13, 14, and 15, and also the oppositely disposed cone or concave shaped recesses on the opposite side 15 or end of the member. It will also be observed that the ribs 20 are arc shaped.

The die is preferably formed by the forging process; the angle of each recess being such that the forging tool may be readily withdrawn. The openings 22 are produced during the forging process. These openings are important and may be termed clearance holes for the chips and oil.

What I claim is:

25. 1. A thread forming die comprising a one piece member which is formed with an opening therethrough with radially arranged projections extending into the opening and having thread forming teeth on the projections and a plurality of cone shaped recesses extending from the outer opposite surfaces of the die and terminating in an arc shaped surface or edge back of the thread forming teeth or cutting edges of 35 the lands and in a plane midway between the opposite faces.

2. A hexagonal thread forming die comprising a one piece member which is formed with an opening therethrough with radially arranged projections extending into the opening and having thread forming teeth on the projections and a plurality of inclined shaped recesses extending from the outer faces of the said die and terminating 45 in an arc shaped edge that is located back of the thread forming teeth or cutting edges of the lands, said inclined recesses being located on opposite sides of the die and the material between the recesses providing 50 strengthening ribs.

55. 3. A die for the purpose described, comprising a member formed with an opening therethrough, a plurality of lands extending into the opening, cone shaped strengthening ribs located between the lands and ar-

ranged in the median plane of the die, whereby the lands are strengthened both transversely and in the median plane the construction and arrangement of the ribs being such that the lands are strengthened 60 both longitudinally and transversely of the die.

4. A hexagonal shaped thread forming die having an opening therethrough, a plurality of thread forming lands on projections which extend axially from one face of the die to the other and strengthening cone shaped ribs in cross section being located intermediate of the length of the lands.

5. A hexagonal die which is formed with an opening through the same, a plurality of thread cutting lands projecting into the opening, a plurality of inclined shaped oppositely located recesses in the die and terminating in cone shaped ribs which are located in a plane represented by the median plane of the die, and means for adjusting the size of the die for varying the diameter of the thread to be formed.

6. A die comprising a member having an opening therethrough, and radially arranged projections extending into the openings and having thread forming teeth on the projections, the portions of the member between the projections and on opposite sides of the member having concave shaped recesses in cross section and the edges of which recesses constitutes the borders of the projections; the border lines being in the opposite faces of the member and the said recesses terminating in a plane that is located midway between the opposite faces of the member.

7. A screw cutting die comprising a member having an opening through the same and which is formed with a plurality of cone-shaped recesses on its opposite outer ends which extend from its outer ends to a plane located substantially midway between its ends, the opening having thread forming lands which project into the opening and the die having a plurality of axially arranged clearance openings for chips and oil which are located between the said lands and the inner ends of the inclined recesses and a strengthening rib midway between the ends of the die.

FRANK O. WELLS.
